TOY VEHICLE WITH SPARK PRODUCING DEVICE

Carl Arnold, Nuremberg, Germany

Application November 1, 1935, Serial No. 47,817
In Germany July 29, 1935

3 Claims. (Cl. 46—10)

The invention relates to a toy vehicle, for instance in the form of an armoured car, tank or the like with spark producing device and characterized in that during the running of the car a 5 turret fitted with gun barrels is rotated by suitable means, a spark producing device also rotated being actuated at the same time. By this arrangement the sparks produced are thrown during the running of the car towards all sides from the turret, whereby a perfect effect is obtained.

An embodiment of the invention is illustrated by way of example in the accompanying drawing in which:—

Fig. 1 shows the toy in section.

Fig. 2 is a top plan view of the toy, the turret being removed.

The vehicle *a* is propelled by a spring motor *b* which at the same time serves for actuating the spark producing device and for rotating this 20 device and also the armoured turret. With this object in view a bridge *c* is fixed on the casing of the spring motor *b*. This bridge *c* has a rivet *d*, lug or the like. Through the bridge and the rivet *d* an axle *g*, carrying a crown wheel *f*, is loosely guided and engages by a gear *h* with the spring 25 motor *b*. The crown wheel *f* in turn rotates different pinions and gear wheels *i* by which the spark producing mechanism *k* is actuated. By the crown wheel gear *f* and parts, *g*, *h*, *i* a rapid 30 rotation is communicated to the spark producing mechanism. The gears *f*, *i* and the spark producing device are rotatably mounted in and enclosed by a casing *l* arranged on a star-shaped plate *m*. This plate *m* is loosely movable on the rivet *d* 35 and is turned by a cam disc *n* or the like, situated on the outer side of the casing of the spring motor, and driven from the spring motor so that the star-shaped plate rotates together with the gears *f*, *i*, and the spark device.

An armoured turret *o* is mounted on the spark 40 device casing and gun barrels project from the same. This turret *o* has apertures *p* through which the sparks are thrown out. It rotates with the casing and is guided in an aperture *q* 45 of the toy vehicle *a*.

If the driving mechanism *b* has been wound, the armoured car moves forward and the crown wheel gear arranged in the casing actuates the spark producing device for producing sparks. By the cam disc also driven from the driving 5 mechanism the star-shaped wheel and the gear rigidly mounted on the same and the spark device casing are rotated and the turret *o* projecting through the aperture *q* of the toy vehicle and mounted on the casing is rotated. This 10 rotating movement is also imparted to the spark producing device. By means of one spring motor rotation of the spark producing device and of the crown wheel gear and a rotating movement 15 of the star-shaped plate, the spark casing and the armoured turret are obtained. The sparks produced by the spark producing mechanism are 20 rotated and produce a splendid effect.

I claim:—

1. A toy vehicle in the form of an armoured 20 car, tank or the like, comprising a spring motor adapted to propel the toy, a casing rotatably mounted on said motor, a crown wheel drive driven by said motor, a spark producing device 25 in said casing actuated by said crown wheel drive, a rivet at the bottom of said casing, a star wheel loosely mounted on said rivet and rigidly connected with said casing, and a cam disc driven by said motor and adapted to rotate said star wheel, said casing and said spark producing 30 device.

2. In a toy vehicle as specified in claim 1, an armoured tower removably fitted on said casing and having apertures for the passage of the sparks, said armature being rotated with said 35 casing through the intermediary of said star wheel and said cam disc.

3. A toy vehicle as specified in claim 1, in which the rivet carrying the star wheel is arranged on a bridge fixed on the spring motor and a crown 40 wheel axle of the crown wheel drive actuating the sparking device extends through said rivet.

CARL ARNOLD.
